UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

ADJUSTABLE BINDER.

1,390,195.

Specification of Letters Patent. Patented Sept. 6, 1921.

Application filed February 1, 1919. Serial No. 274,461.

To all whom it may concern:

Be it known that I, ALBERT H. DE VOE, a citizen of the United States, residing at Westfield, in the county of Union and State 5 of New Jersey, have invented certain new and useful Improvements in Adjustable Binders, of which the following is a specification, reference being had therein to the accompanying drawings.

10 This invention relates to an adjustable binder suitable for ready attachment to the cloth-plate of a sewing machine.

The objects of the invention are to provide a simple, economically manufactured binder 15 having a maximum number of adjustments with the fewest parts, and to more certainly prevent unfolding of the binding strip before it reaches the stitching point.

In the preferred form the invention comprises a base provided with means for adjustably securing it to the cloth-plate of a 20 sewing machine. A pair of spaced and relatively inclined guides having in-turned lips for folding and guiding a binding strip are 25 disposed to one side of the base, said guides having supports movable in channels cut in the upper and lower surfaces of the base. These guides, while capable of individual 30 adjustment, are secured to the base by a single clamp-screw. Between the guides and opposed to their in-turned edges is a member having a concaved surface forming an edge-gage for the work as well as acting as an additional guide for the binding 35 strip. This member has a support offset from the guides and adjustably secured to the base. The in-turned folding lips terminate short of the discharge end of the binder and one of the guides has a vertical flange 40 beyond its folding lip and extending toward the discharge end of the binder to prevent the binding strip from unfolding. The inner gage and guide-member has a projection extending beyond the binder which 45 acts as a guide as the work approaches the stitching point.

In the accompanying drawings, Figure 1 is a top plan view of the binder. Fig. 2 is a bottom plan. Fig. 3 is an end elevation. 50 Fig. 4 is a side elevation. Fig. 5 is a transverse section taken through the guides, and Fig. 6 is a section at right angles to that in Fig. 5.

55 Referring to the drawings 1 is the base of the binder having the slot 2 through

which it may be adjustably secured to the cloth-plate of the machine by means of clamp-screw 3. Formed in the upper and lower surfaces of the base are the respective channels 4 and 5 (Fig. 6) in which fit 60 the adjustable guide supports 6 and 7. The support 6 has a slot 8 therein, and the support 7 has an upwardly projecting lug 9 65 slidable in a slot 10 in the base. A thumb-screw 11 has a stem-portion 12 passing 70 through the slot 8 and threaded into the lug 9, thereby holding the supports 6 and 7 in relatively adjusted position on the base. At one side of the base the supports 6 and 7 carry the respective binder-guides 13 and 14. These guides are relatively inclined as 75 shown in Fig. 4 and at their outer edges have in-turned folding lips 15 of well known form. The lips do not extend along the entire edges of the guides but terminate at 80 a point where, due to the inclination of the guides, the work commences to be crowded. To prevent the folded edge of the binding strip from becoming unfolded after it passes the lips 15 the upper guide is provided with 85 a downwardly extending flange 16 beyond the point where the upper lip 15 terminates. The base 1 is provided with a channel 17 on its upper surface in which is slidable a support 18. A clamp-screw 19 has a stem 20 90 passing through a slot 21 in the support 18 and threaded into the base 1. At one side of the base the support 18 carries an offset gage and guide member 22 which extends between the guides 13 and 14 and 95 terminates in a reduced portion 23 beyond the discharge end of the binder. The guide-member 22 has a concaved surface 24 which is opposite the lips 15. The upper and lower surfaces of the part 22 have shallow 100 notches rearwardly of the points 25, which allows the discharge ends of the guides 13 and 14 to be brought closer together, as shown in Fig. 4. The shoulders formed at the points 25 also act as steadyng and guiding means for the discharge edges of the guides 13 and 14 when the latter are extended from the base, as shown in Figs. 1 and 2.

In the operation of the device the binding 105 strip is fed in between the guides 13 and 14 and folded by the lips 15 and concaved surface 24 in a well known manner around the work disposed between the lips 15. Owing to the proximity of the inclined guides 13 110

and 14 at the point where the work leaves the binder the folding lips 15 terminate short of this point to allow room for the work and binding strip, but to prevent any possible 5 unfolding of the turned-in edges of the binding strip the upper guide 13 is provided with the downwardly directed flange 16. The reduced portion 23 aids in guiding the work to the stitching point after it has left 10 the binder. It will be noted that while the device is simple and contains few parts numerous adjustments are possible. By simply loosening the clamp-screw 11 the guides 13 and 14 may be independently or 15 simultaneously adjusted relatively to the base and to the gage and guide member 22. By loosening the set-screw 19 the gage member 22 may be adjusted relatively to the guides 13 and 14 and to the base, and by 20 loosening set-screw 3 the entire binder may be adjusted on the throat-plate of the machine. The object of all these adjustments is to vary the positions of the parts relatively to the needle 26, to suit varying binding requirements.

Having thus set forth the nature of the invention, what I claim herein is—

1. In a binder, a base adapted to be adjustably secured to a sewing machine cloth-plate, opposed binding guides having supports independently slidably adjustable with respect to said base, unitary means for securing said guides to said base in adjusted position, an independent guide and gage means 30 adjustable toward and from said guides, and means for securing the latter, said means being separate from the means for securing the binding guides.
2. In a binder, a base, means for adjust- 40 ably securing said base to a sewing machine cloth-plate, opposed channels formed in the base, a binding guide having a support slid- able in one of said channels, a second bind- ing guide having a slotted support slid- 45 able in the other channel, said base having a slot in alinement with the slot in the support, a clamp-screw passing through said slots and

threaded into said first support, a guide and gage coöperating with said first-mentioned guides and means for independently adjust- 50 ing it on the base.

3. In a binder, a base, opposed binding guides slidably secured on opposite sides of said base, unitary means for securing said guides, a guide and gage interposed between 55 said guides and having an offset support, and means for adjustably securing said support to the base.

4. In a binder, a base, a pair of relatively inclined binding guides adjustable thereon 60 and having opposed inturned lips terminating short of their proximate ends, one of said guides having a guide-flange extending therefrom beyond its in-turned lip, and an inner opposed gage and guide disposed between said first guides.

5. In a binder, a base, a pair of relatively inclined separated binding guides having in-turned folding lips terminating short of the discharge end of the binder, an edge flange 70 on one of said guides between its lip and said discharge end to guide the binding strip, and an inner opposed work gage and guide between said first guides and having a guide extension projecting beyond the discharge 75 end of the binder.

6. In a binder, a base, a pair of relatively inclined binding and folding guides inde- 80 pendently adjustable on said base, and a work-gage disposed between said guides and independently adjustable on said base, said gage extending beyond said guides and hav- ing notched portions forming bearings for said guides.

7. In a binder, a base, opposed binding guides adjustably secured to said base, unitary means for securing both said guides to the base, a guide and gage interposed between said guides and having a support, and means independent of said first means for 90 adjustably securing said support to the base.

In testimony whereof I have signed my name to this specification.

ALBERT H. DE VOE.
